UNITED STATES PATENT OFFICE.

JUNIUS H. FLINT, OF SALEM, MASSACHUSETTS.

PUZZLE.

SPECIFICATION forming part of Letters Patent No. 562,384, dated June 23, 1896.

Application filed January 27, 1896. Serial No. 576,918. (No model.)

To all whom it may concern:

Be it known that I, JUNIUS H. FLINT, residing at Salem, in the county of Essex and Commonwealth of Massachusetts, have invented 5 a certain new and useful Improvement in Toy Puzzles, of which the following, taken in connection with the accompanying drawings, is a specification.

The present invention relates to improvements in devices of the class of toy puzzles consisting generally of a board having pockets in which balls are deposited by rocking or shaking the board by hand; and it consists of the improved form and arrangement of 15 parts and of the novel combinations herein-after described and claimed.

The present invention is illustrated in the accompanying drawings, in which—

Figure 1 is a plan view of a toy puzzle embodying the same, showing the balls loose upon the board. Fig. 2 is a section on line x x , Fig. 3; and Fig. 3 is a plan view showing the balls in the pockets.

Similar letters of reference indicate like parts throughout the several views.

In the drawings, A represents the board of my improved puzzle, which is provided with the sides a , of cardboard or other suitable material, which keep the balls, hereinafter 30 described, upon the board A. To the board A are secured the pins b , which are arranged thereon in groups to form the rectangular pens or pockets B B' B^2 .

The pockets B , B' , and B^2 are arranged in 35 three rows, running straight across the board A, two of the rows being placed adjacent to opposite ends, and the third located at or near the center of the board A.

The pockets B , B' , and B^2 are open at one 40 end and closed at the other. The pockets B and B^2 in the two outer rows open toward each other, and the pockets B , in the intermediate row, open alternately in opposite directions, so that one pocket B opens in the 45 same direction that the pockets B' open, and the next adjacent pocket B opens in the same direction that the pockets B^2 open. This arrangement of pockets makes the puzzle very difficult of solution, since the tendency is for 50 any of the balls which have been caught in the outer pockets to become displaced while

effort is being made to place other of the balls in the intermediate pockets, and vice versa.

To further increase the difficulty of solving the puzzle, the pockets B B' B^2 are formed of 55 different widths, the most difficult arrangement being that shown in the drawings, in which the width of each pocket differs from that of every other pocket.

f , f , &c., represent a series of removable 60 balls, which are adapted to enter the pockets B , B' , and B^2 . In practice the balls f are the common form of toy marbles. In their form the balls f are of different diameters, so that any ball f will enter certain of the pockets B , 65 B' , and B^2 , and will not enter other of said pockets.

The arrangement which makes the puzzle the most difficult of solution is that shown in the drawings, in which the diameter of 70 each ball f differs from the diameter of every other ball f , and corresponds substantially with the diameter of one of the pockets.

It will be readily seen that, with the arrangement last described, to place all the 75 balls in the pockets, and each in a separate pocket, requires each ball to be placed in the particular pocket to which it is fitted.

As shown, there is one ball for each pocket, but if desired two or more balls may be fitted to 80 enter the same pocket and such arrangement will involve no departure from the present invention.

The puzzle is solved by taking the board in the hand, the balls being loose thereon, and 85 so manipulating it that a ball is placed in each of the pockets, it being of course understood that the balls are not to be touched by the fingers.

Having thus described my invention and its 90 use, I claim as novel and desire to secure by Letters Patent of the United States—

1. As an improvement in toy puzzles the herein-described rectangular board as A having the sides or flanges a and provided with 95 pockets as B B' B^2 , one at each of the corners said pockets opening inward and lengthwise of the board and with pockets as B B near the center of the board, said pockets also opening lengthwise of the board and in opposite directions, the openings in the several 100 pockets being of different sizes and adapted

- to receive different-sized balls which roll upon the board, said balls corresponding in number and size with the openings in the pockets, substantially as shown and described.
- 5 2. The combination of the rectangular board A provided with the sides or flanges α and pockets as B', B' B², B² B, B arranged at the corners and near the middle of the board, the corner-pockets arranged to face each other 10 and those at the center facing lengthwise of the board and in opposite directions, the several pockets being each provided with an opening differing in size from the others, with the balls f f adapted to roll on the board and of numbers and sizes corresponding to the 15 openings in the pockets on said board, substantially as described.
3. A rectangular board having raised flanges about its edges as α and a series of pockets for the reception of balls as B, B' B'', having openings each differing in size, said board to be used with balls to be rolled upon it corresponding in numbers and sizes with the said openings in the pockets, substantially as set forth and described. 20
- 25 In testimony whereof I have hereunto set my hand, in the presence of two attesting witnesses, at said Lynn, this 23d day of January, 1896.

JUNIUS H. FLINT.
